UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

DESIGN FOR A CAP FOR A TALCUM-POWDER BOX.

58,417.

Specification for Design.

Patented July 12, 1921.

Application filed September 23, 1920. Serial No. 412,365. Term of patent 14 years.

To all whom it may concern:

Be it known that I, JOHN M. HOTHERSALL, a citizen of the United States, residing at Brooklyn, in the county of Kings and State of New York, have invented a new, original, and ornamental Design for a Cap for Talcum-Powder Boxes, of which the following is a specification, reference being had to the accompanying drawing, form a part thereof.

On the drawing,

Figure 1 is a perspective view of a cap embodying my present invention;

Fig. 2 is a side elevation of the cap.

I claim:

The ornamental design for a cap for a talcum powder box, as shown.

JOHN M. HOTHERSALL.

Witnesses:

H. B. KORWAN,
F. H. BECKMAN.
